UNITED STATES PATENT OFFICE.

FRANK EDMUND HAVLIN, OF NORWOOD, OHIO.

DESIGN FOR A BICYCLE-SADDLE.

SPECIFICATION forming part of Design No. 25,485, dated May 12, 1896.

Application filed February 28, 1896. Serial No. 581,208. Term of patent 7 years.

To all whom it may concern:

Be it known that I, FRANK EDMUND HAVLIN, a citizen of the United States, residing at Norwood, in the county of Hamilton and State 5 of Ohio, have invented a new and original Design for Bicycle-Saddles, which improvement is fully set forth in the following specification and accompanying drawings, in which—

Figure 1 is a plan view of a saddle, showing 10 my design; and Fig. 2 a general perspective view.

The principal features of the design will be apparent by referring to the accompanying drawings, in which it will be seen that the 15 saddle is bifurcated by a central slot or opening A, extending rearwardly from the front. It will be observed that the slot does not approximate the rear edge so closely as to impair the strength or rigidity of the structure. 20 Midway between the said slot and the outer sides of the saddle are apertures B and C, which are preferably elliptical in form.

When viewed from the side, the saddle exhibits a slightly-protuberant surface, the upper corners of the sides and rear and those 25 bordering the central slot and the apertures B and C being uniformly rounded.

The design presents an exceptionally novel and comely appearance, and in practical use will prove conducive to the comfort, as well 30 as the health of the rider.

What I claim as new is—

The design for a saddle substantially as herein shown and described.

In testimony that I claim the foregoing I 35 have hereunto set my hand, this 10th day of February, 1896, in the presence of witnesses.

FRANK EDMUND HAVLIN.
